Thonet Brothers, Inc., New York, N. Y.

Application July 9, 1945, Serial No. 120,594

Term of patent 7 years

(Cl. D15—1)

To all whom it may concern:

Be it known that I, Bruno R. Weill, a citizen of France, residing at Statesville, in the county of Iredell and State of North Carolina, have invented a new, original, and ornamental Design for Chair or Similar Article, of which the following is a specification, reference being had to the accompanying drawing, forming part thereof.

In the drawing:

Fig. 1 is a front perspective view of the chair or similar article showing my new design;

Fig. 2 is a rear view in elevation of the chair or similar article as shown in Fig. 1.

I claim:

The ornamental design for a chair or similar article, as shown.

BRUNO R. WEILL.
